DESIGN FOR A COMBINATION BUMPER AND HANGER FOR MOP HANDLES

Frederick A. Speik, South Pasadena, Calif., as-
signor to Robert L. Speik, South Pasadena,
Calif.

Application May 28, 1940, Serial No. 92,658

Term of patent 7 years

To all whom it may concern:

Be it known that I, Frederick A. Speik, a citizen of the United States, residing at South Pasadena, in the county of Los Angeles and State of California, have invented a new, original, and ornamental Design for Combination Bumper and Hanger for Mop Handles, of which the following is a specification, reference being had to the accompanying drawing, forming part thereof.

Figure 1 is a front elevational view;

Figure 2 is a vertical cross line on line 2—2 of Fig. 1;

Fig. 3 is a top plan view, and

Fig. 4 is a bottom plan view of a combination bumper and hanger for mop handles showing my new design.

I claim:

The ornamental design for a combination bumper and hanger for mop handles, as shown.

FREDERICK A. SPEIK.
